DESIGN FOR A DRESS

Frederick Martin Bob Burns, New York, N. Y.

Application January 26, 1938, Serial No. 74,559

Term of patent 3½ years

To all whom it may concern:

Be it known that I, Frederick Martin Bob Burns, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress as shown, of the contrasting detachable sleeve and front waist extended inserts, as shown.

I claim:

The ornamental design for a dress substantially as shown and described.

FREDERICK MARTIN BOB BURNS,
